UNITED STATES PATENT OFFICE.

JEDDY D. NIXON, OF HOUSTON, TEXAS, ASSIGNOR TO HOWARD F. SMITH, OF HARRIS COUNTY, TEXAS.

DOUBLE-ACTING TONG.

Application filed March 6, 1922. Serial No. 541,611.

To all whom it may concern:

Be it known that I, JEDDY D. NIXON, a citizen of the United States, residing at Houston, in the county of Harris and State 5 of Texas, have invented certain new and useful Improvement in a Double-Acting Tong, of which the following is a specification.

This invention relates to new and useful improvements in a double acting tong.

10 One object of the invention is to provide a tong of the character described specially designed for screwing and unscrewing joints of pipe and for turning other round objects.

15 Another object of the invention is to provide a tong of the character described which is so constructed that it will readily grip the pipe, or other object to turn it in either direction.

20 A further feature of the invention resides in the provision of a novel means for suspending the tong in its proper relation to the work.

With the above and other objects in view 25 the invention has particular relation to certain novel features of construction, operation and arrangement of parts, an example of which is given in this specification and illustrated in the accompanying drawings,

30 wherein:—

Figure 1 is a plan view of the tong.

Figure 2 is an edge view.

Figure 3 is a fragmentary plan view.

Figure 4 is a detailed view of the latch.

35 Figure 5 shows a plan view of the tong and the suspending means therefor, and

Figure 6 shows a side view thereof.

Referring now more particularly to the drawings, the numeral 1 designates the tong handle, one end of which is enlarged forming the head 2, said head consisting of the upper and lower plates 3, 3, which are spaced apart, and formed integrally with the handle. The numerals 4, 4 designate the jaws 40 which are arcuate in general contour, and which are formed with the flattened shanks, 5, 5, which fit between the plates 3. The inner end of each shank has an opening 6 therethrough, aligned with corresponding openings 7, 7 through the upper and lower plates and in front of the openings 6, each shank has an oblong slot 8, 8 aligned with the corresponding opening 6, said slots lying in substantially parallel relation with the longitudinal axis of the handle. The plates 3

are also provided with the aligned openings 9, 9 arranged in front of the openings 7. Pins 10, 10 are provided. One of these pins is fitted through the aligned openings 7 of the plates 3 and through the corresponding opening 6, of one of the jaws 4 and the other pin works through the aligned openings 9 of the plates and through the slot 8 of the other jaw 4. The position of these pins are reversed when it is desired to reverse the 60 action of the tong, that is when it is desired to manipulate the tong in the other direction.

Hinged to the free end of one of the jaws 4 there is a latch 11 whose free end has the 70 opposing lateral lugs 12, 12, and the free end of the other jaw 4 has a notch 13 into which the latch engages to hold said jaws in closed position around the pipe. Underneath the pivoted end of the latch the jaw to which it is 75 pivoted has a socket 14 in which there is fitted a coil spring 15, which presses against the shoulder 16 of the latch to hold it against accidental disengagement from the other jaw. The inner side of each jaw has suitable 80 teeth for engagement with the pipe to be turned. These teeth 17 may be made detachable, if desired, and any number of teeth may be employed.

In Figure 1 the wrench is shown in position, as engaged around the pipe and the pins 10 are disposed to cause the jaws to grip the pipe, when the tong is turned in a left hand, or anti-clock wise direction. In this position the shanks of the jaws are spaced 85 apart. When power is applied to the handle it will assume the position shown in Figure 3, and one of the pins 10 traveling the slot 8 will describe an arc and force the jaws together to grip the pipe. If the tong is to 90 be manipulated in the other direction the position of the pins 10 should be reversed.

In Figures 5 and 6 I have shown means for suspending the tong in position to be applied to the pipe. These suspending 100 means are necessary for the reason that the tong is usually too heavy to be easily handled. Each side of the upper plate 3 has an ear 18 in which there is threaded a hook 19 and near the outer end of the handle there 105 is a similar hook 20. The tong is suspended from the derrick, by means of a cable 21, whose lower end has a ring 22. A chain 23 is connected at one end to said ring and at the other end to the hook 20. Chains 110

24, 24 are connected at their lower ends to the hooks 19 and their upper ends are connected to the ring 25, and the rings 22 and 25 are connected by a chain 26. The means of suspending the tong above described, prevent the same from tilting either endwise or laterally.

What I claim is:

1. A tong including a handle, spaced head-
10 plates carried by one end of the handle, and
extending laterally each way beyond the
handle, a pair of jaws formed with similar
shanks which fit between the extended
15 portions of said plates, each shank having
a bearing and an oblong slot, a bearing pin
carried by the head-plates, and passing
through the bearing of one shank and forming
20 a stationary pivot bearing therefor, and
a bearing pin carried by said plates and
passing through the slot of the other shank,
the respective pins forming the only means
for connecting the jaws to the handle, means
25 for securing the jaws around the object to
be turned.
2. A tong including a handle, spaced

head-plates carried by one end of the handle, and extending laterally each way beyond the handle, a pair of jaws formed with similar shanks which fit between the extended portions of said plates, each shank having a bearing and an oblong slot, a bearing pin carried by the head-plates, and passing through the bearing of one shank and forming a stationary pivot bearing therefor, and a bearing pin carried by said plates and passing through the slot of the other shank, the respective pins forming the only means for connecting the jaws to the handle, means for securing the jaws around the object to be turned, said bearing pins being interchangeable with respect to the bearing and slot of the shanks.

In testimony whereof I have signed my name to this specification in the presence of two subscribing witnesses.

JEDDY D. NIXON.
